UNITED STATES PATENT OFFICE.

DANIEL C. SPRUANCE, OF PHILADELPHIA, PENNSYLVANIA, AND MONTGOMERY WADDELL, OF NEW YORK, N. Y., ASSIGNORS TO THE SENTINEL ELECTRIC COMPANY, OF WILMINGTON, DELAWARE.

ELECTROMAGNETIC-CIRCUIT BREAKER.

SPECIFICATION forming part of Letters Patent No. 593,167, dated November 2, 1897.

Application filed January 25, 1897. Serial No. 620,532. (No model.)

To all whom it may concern:

Be it known that we, DANIEL C. SPRUANCE, a citizen of the United States, residing at Philadelphia, in the county of Philadelphia and State of Pennsylvania, and MONTGOMERY WADDELL, a subject of the Queen of Great Britain, residing at New York, in the county of New York and State of New York, have invented certain new and useful Improvements in Electromagnetic-Circuit Breakers, of which the following is a full, clear, and exact description.

This invention relates to electromagnetic-circuit breakers, the primary object being to provide an apparatus that will positively open an electric circuit under certain prearranged conditions in such a manner that there can be no possibility of the circuit being completed or left in such a condition as will cause an arc to be formed by the accidental return to position of the section of the circuit wherein the opening is made.

A further object is to provide a sensitive instrument, one easily and accurately adjustable to operate under various current-amperages, and one which may be readily reset after having operated.

The invention consists, first, in the method of opening a circuit by mechanically breaking out a section thereof from between two terminals; second, in certain latch-and-trigger mechanisms, and, third, in the details of construction.

The invention is illustrated in the accompanying drawings, in which—

Figure 1 is a front elevation of the improved circuit-breaker, and Fig. 2 is a side elevation of the same.

Referring to the drawings by letter, A represents a base of insulating material, such as slate or marble, upon which the parts of the circuit-breaker are mounted.

a and *a'* are two binding-posts to which the wires of the circuit are connected and between which the instrument is interposed. Upon the face of the base and along its central vertical line are permanently mounted two terminal clips *b* and *b'*, respectively, provided with rectangular openings near their outer ends adapted to receive a metallic bar

s, forming a part of the circuit. The clip nearest the binding-post *a'* is conductively connected therewith by a lug *b*². Above the upper clip is placed an electromagnet consisting of a core *e* and a coil *e'*. The core is 55 in the form of a ring or other closed figure having a segment removed to determine the location of its poles and the operating position of the armature. This opening is made in the upper outer side of the ring. The core 60 consists of a series of thin plates of soft iron confined between two end plates *e*² *e*², which latter have extending brackets *e*³, by which the core is secured to the base A. The coil 65 *e'* consists of several turns of bare wire coiled about the core in such a manner as not to touch each other nor the core. One terminal of the coil connects with the clip *b'*, while the other terminal leads through a suitable opening and a groove in the base A to the 70 binding-post *a*.

The armature of the magnet is represented by *f*. It is supported at the extremities of two arms *f'*, pivoted at their opposite ends upon a shaft *g*. The armature normally 75 stands within the inclosure of the core and the arms *f'* straddle the core. The armature is supported in its normal or retracted position by an arm *h*, attached at one end to the shaft *g* and engaging with a ratchet *i* at its 80 other end. This arm has a kink or bend *h*' in it, by compressing the sides of which the arm may be slightly shortened to change its point of engagement with the ratchet and thus alter the distance of the armature from 85 the poles. A brass frame *l*, consisting of two plates secured to the opposite sides of the core of the magnet, is used to support the shaft *g*, the ratchet *i*, and another shaft *j*. The ratchet is formed directly in an extension *i*' from this frame, the extension flanking both sides of the core and the teeth being cut in each at corresponding points. A scale, as will be seen, is marked upon the ratchet for the purpose of indicating where the arm 95 *h* should be set to determine when the circuit-breaker shall perform its function of opening the circuit. The figures of the scale will indicate a graduation of amperes of current at any point between the limits of which 100

the armature may be set to alter the attractive distance between magnet and armature.

5 *o* indicates a latch-lever in the form of a yoke. Its two arms embrace the magnet-core and are pivoted at their extremities upon the ends of the shaft *j*. The cross connection of the yoke stands in behind the magnet-core near the base *A* and carries a tailpiece *o'*, projecting downward from its middle point 10 and having a slightly curved or hooked end *o''*. The outer extremities of the yoke have eccentric hooks *o'''* formed thereupon, and these, for the sake of strength and rigidity, are connected together by a cross-bar *o''''*.

15 *p* is a lever performing the functions of a trigger. It is pivoted upon the shaft *g* and has an outwardly-reaching arm terminating in a finger-piece *p'* and an inwardly-reaching arm provided with a shoulder *p''* and a hook 20 *p'''*, the latter being located in the same vertical plane as the tailpiece *o'* on the yoke or latch-lever. The outwardly-reaching arm is provided with a lug *p''''*, extending into the space between the pole-pieces of the magnet-core.

25 *r* is a yoke of heavy stiff wire, which we will call the "hammer." Its terminals are coiled up into two heavy springs *r' r''*, the ends of which are firmly secured into the base *A*. These two springs are placed in line 30 with each other upon opposite sides of the magnet-core near the base and are held in place by a transverse rod *r''''*, extending through the side plates supporting the core 35 of the magnet and lying against the inner surface of the springs on each side. The tendency of the spring is to force the hammer toward the face of the base *A*, and in this position the hammer rests upon two rubber 40 cushions *t t*. The radial length of the hammer is such that it will swing midway between the two clips *b b'* and will engage with the hooks *o''* on the latch-lever.

45 The metallic bar *s*, hereinbefore referred to, forms a section of the circuit interposed between the clips *b* and *b'*. This bar is adapted to be broken by the hammer in such a way as to absolutely remove a section of it from between the two fixed clips, and to this 50 end it is formed with a number of transverse weakening-grooves *s'* to determine where it shall be broken. We prefer to have three of these grooves and to arrange one of them near the middle point of the bar and the 55 other two respectively adjacent to the clips, so that the blow delivered by the hammer near the middle point of the bar will fracture it at three points and remove a section of the circuit in two pieces. This precludes the 60 possibility of the removed section from rebounding or otherwise accidentally ridging the two clips and so closing or partially closing the circuit immediately after it has been opened. This obviously would be accomplished if the bar were broken into any number of pieces above two, and consequently the 65 invention comprehends not only the removal

of a section of the circuit from between two fixed terminals, but also the breaking up of the removed section into a plurality of pieces. 7c

The operation of the circuit-breaker is as follows: The normal position of the parts is shown in Fig. 2, wherein it will be seen that the hammer has been elevated and is held against the tension of its springs by the 75 hooks *o'*, the latch-yoke *o* being locked by contact with the shoulder *p''* on the trigger. When the current in the circuit rises to a predetermined maximum, the strength of the magnet becomes sufficient to lift the armature into the gap between the two poles of the magnet-core and cause it to strike a blow against the lug *p''''* on the trigger and swing the inner end of the trigger outward, thus releasing the yoke and allowing the hooks *o''* to 80 tilt downward sufficiently to free the hammer. The springs controlling the hammer cause it to make a quick powerful stroke across the middle of the bar *s* and shatter it along the weakened lines, thus mechanically removing 85 a section of the circuit bodily from between the two terminals *b b'*. After fracturing the bar the hammer comes to rest upon the cushions *t t*. The tilting of the yoke *o* to release the hammer causes the inner end of the 90 yoke to rise until the hooked extremity of the tailpiece *o'* passes above the hook *p'''* on the trigger, which latter then passes under the end of the tail piece and holds the inner end of the latch-yoke in its elevated position. 95 This is convenient in resetting the instrument, for in this position the eccentric hooks *o''* are tilted to permit the hammer to pass behind them. The hammer having passed the hooks, it is carried slightly beyond to 100 strike and lift the outer end of the trigger and so remove hook *p'''* from the tailpiece of the latch, allowing it to drop to carry the hooks in front of the lever, in which position it again becomes locked by engagement with the shoulder *p''* and will sustain the hammer. 105

Having thus described our invention, we claim—

1. The method of opening an electric circuit which consists in mechanically breaking out by a hammer-blow a section of the circuit from between two terminals, and simultaneously breaking the removed section into a plurality of parts. 115

2. In an electric-circuit breaker, the combination of a breakable bar forming a section of the circuit and a hammer adapted to strike and break said bar, substantially as described. 120

3. In an electric-circuit breaker, the combination of a breakable bar forming a section of the circuit, a hammer adapted to strike and break said bar and an electromagnet controlling said hammer, substantially as described. 125

4. In an electric-circuit breaker, the combination of a breakable bar forming a section of a circuit, a hammer adapted to strike and break said bar, a latch supporting said hammer in position to strike, a trigger for releas- 130

- ing the latch and an electromagnet whose armature is adapted to operate the trigger, substantially as described.
5. In an electromagnetic-circuit breaker the combination of the breakable bar forming a section of the circuit, a hammer adapted to strike and break said bar, a latch supporting said hammer in position to strike, a trigger adapted to hold the latch in its operative position and to release the same, a detent for the latch adapted to hold it in its inoperative position, and an electromagnet whose armature operates the trigger, for the purpose set forth.
10. In an electromagnetic-circuit breaker, the combination of a breakable bar forming a section of a circuit, a hammer adapted to strike and break said bar, a latch supporting said hammer in position to strike, a trigger provided with two detents, one adapted to sustain the latch in its operative position and the other to sustain it in its inoperative position and an electromagnet whose armature operates the trigger.
15. In a circuit-breaker an electromagnet having a ring, or other closed-shaped core whose armature-space is formed by removing a segment thereof, an armature for said magnet normally located within said ring, a trigger projecting into the armature-space and adapted to be moved by the armature, a latch controlled by the trigger and a circuit-con-
- trolling device held in operative position by the latch, substantially as described.
20. In an electromagnetic-circuit breaker, an electromagnet having a ring or other closed-shaped core, a segment of which is removed to form the armature-space, in combination with an armature normally wholly within the figure of the core and out of the armature-space and adapted to move bodily into the armature-space, for the purpose set forth.
25. In an electromagnetic-circuit breaker an electromagnet having a ring or other shaped core, a segment of which is removed to form the armature-space, an armature located within said ring, a pivoted arm normally supporting the armature and a ratchet sustaining said arm and along which it is adjustable, substantially as and for the purpose described.
30. In a circuit-breaker, a breakable bar forming a section of the circuit, a spring-operated hammer in the form of a yoke, the cross-piece of which is adapted to strike and fracture the said strip.
35. In testimony whereof we subscribe our signatures in presence of two witnesses.
